United States Patent Office

Des. 198,382
Patented June 9, 1964

198,382

GAME BOARD

Jerome J. Donnellon, 7958 Dimmick Road,
Cincinnati, Ohio

Filed Sept. 5, 1963, Ser. No. 76,492

Term of patent 14 years

(Cl. D34—5)

The figure is a plan view of a game board showing my new design, said board being of conventional thickness and the dominant features of the design reside in the portions shown in full lines.

I claim:

The ornamental design for a game board, as shown and described.
